CLAIM

The ornamental design for a medical article for treating a wound and/or scar tissue, as shown and described.

DESCRIPTION

FIG. 1 is a top perspective view of a medical article for treating a wound and/or scar tissue, in accordance with the present invention;

FIG. 2 is a top plan view of the medical article of FIG. 1;

FIG. 3 is a bottom plan view of the medical article of FIG. 1;

FIG. 4 is a front elevation view of the medical article of FIG. 1;

FIG. 5 is a rear elevation view of the medical article of FIG. 1;

FIG. 6 is a right elevation view of the medical article of FIG. 1; and,

FIG. 7 is a left elevation view of the medical article of FIG. 1.

In the drawings, the broken lines show portions of a medical article for treating a wound and/or scar tissue that form no part of the claimed design.
